TRAY

Frank M. Crook, Toledo, Ohio, assignor to The Toledo Desk & Fixture Company, Maumee, Ohio, a corporation of Ohio

Application July 31, 1948, Serial No. 147,871

Term of patent 3½ years

(Cl. D44—10)

To all whom it may concern:

Be it known that I, Frank M. Crook, a citizen of the United States and resident of Toledo, in the county of Lucas and State of Ohio, have invented a new, original, and ornamental Design for a Tray, of which the following is a specification, reference being had to the accompanying drawing forming a part thereof.

Fig. 1 is a perspective view of a tray showing my new design;

Fig. 2 is a perspective view of the opposite face;

Fig. 3 is a cross sectional view thereof taken on line 3—3 of Fig. 2.

The dominant features of the design reside in the parts shown in full lines.

I claim:

The ornamental design for a tray, substantially as shown and described.

FRANK M. CROOK.
